United States Patent Office.

CONRAD HARRIS AND PAUL W. ZOINER, OF CINCINNATI, OHIO.

Design No. 2,606, dated March 26, 1867.

DESIGN FOR A PARLOR STOVE.

The Schedule referred to in these Letters Patent and making part of the same.

TO ALL WHOM IT MAY CONCERN:

Be it known that we, CONRAD HARRIS and PAUL W. ZOINER, both of Cincinnati, county of Hamilton, State of Ohio, have invented a new and useful Design for Coal Parlor Stoves, to be known and called the Moderator; and we do hereby declare that the following is a full and exact description thereof, reference being had to the accompanying photographs, showing a perspective view of the stove.

What we claim as our invention, and desire to secure by Letters Patent, is—

The design for coal parlor stoves, as shown and described.

C. HARRIS,
PAUL WILLIAM ZOINER.
